BAFFLE FOR AIR DUCTS OF GENERATOR COOLERS

William M. Kennedy, Lyndhurst, N. J.

Application April 20, 1949, Serial No. 88,609

5 Claims. (Cl. 62—140)

1

This invention relates to cooling systems as employed in connection with turbine driving generators. Still more particularly, the invention deals with the use of condensation collecting and dispensing baffles in air ducts of cooling units of this type and kind, thereby increasing efficiency of, and maintain operation of such units.

The novel features of the invention will be best understood from the following description when taken together with the accompanying drawing, in which certain embodiments of the invention are disclosed, and in which the separate parts are designated by suitable reference characters in each of the views; and in which:

Fig. 1 is a diagrammatic side view of a generator showing a cooling unit operating in conjunction therewith, with parts of the construction broken away; and

Fig. 2 is a partial section on the line 2—2 of Fig. 1.

In Fig. 1 of the drawing, I have diagrammatically illustrated at 5, a generator driven from a turbine or other motor shaft 6, and at 7 I have indicated diagrammatically, a cooling unit for generators of this type and kind. This unit comprises an air duct coupled with and communicating with opposed sides of the generator, as seen at 8 and 9. The air duct comprises one tube or housing 10 extending upwardly from the attached end 8 and in the tube 10 is disposed a fan housing 11 driven by an electric motor 12. The upper end of the duct or housing 10 communicates with a horizontal duct or housing portion 13, which in turn communicates with another vertical duct or housing 14, the latter communicating with the generator at the end 9. In the upper end of the vertical portion 14 of the housing or air duct, is disposed an air cooling mechanism 15 in the form of a series of pipe coils 16 through which cool water, or other cooling means is circulated, as in other devices of this type and kind, inlet and outlet of the cooling medium being disposed at the header 17.

Beneath the coils 16, the air duct 14 has a series of baffles 18, 19, 19' and 20, as indicated in section in Fig. 2 of the drawing. The baffle 18 is disposed centrally of the air duct 14 and comprises downwardly inclined side plates 21 terminating at their lower ends in upwardly and inwardly curved trough-like portions 22 having

5 at one side of the air duct 14, discharges 23 to a common drain pipe 24. The troughs 22 terminate short of the opposed walls of the air duct to provide air circulating spaces 25. It will appear that the baffles 19 are disposed directly below the circulating passages 25 and comprise upwardly inclined walls 26 terminating at their upper end portions in upwardly and outwardly curved flanges 27, which lie beneath the baffle 18 well inwardly of the trough 22. This produces a central circulating passage 28 in the duct 14, as will be apparent. Suitable discharges 29 are provided at the lower ends of the baffle adjacent the side walls of the duct 14 which open into a common drain 30.

20 Beneath the air circulating passage 28 and centrally of the air duct 14 is disposed the baffle 20 which is reversed with respect to the arrangement of the baffle 18 in the sense that it has upwardly and laterally flared walls 31 forming a trough-like structure of the baffle 20 at the base of which is a discharge 32 opening into a drain 33. Upper ends of the walls 31 have inwardly turned flanges 34 and these ends are spaced inwardly of the side walls of the air duct to form other circulating passages 35, similar to the passages 25.

25 From the foregoing, it will be apparent that as air is circulated through the cooling unit 7, it passes upwardly through the side 10 of the air duct, across the upper part 13 of this air duct, down and around the pipe coils 16, and then through the circulating passages 25, 28 and 35, and thus through the generator.

30 Passage of heated air over the pipe coils 16 develops condensation, which condensation drops onto the baffles or is picked up by the baffles in the circulation of air through the duct 14 or the passages 25, 28 and 35 thereof, and this condensation is discharged through the drain or discharges 24, 30 and 33. By overlapping adjacent baffles, in the manner illustrated, greater assurance of picking-up the condensate is provided, and by disposing of this condensate, the danger of 35 destroying the generator is substantially eliminated. Circulation of moist air through generators of the kind under consideration can become extremely destructive and by providing baffles of the type and kind illustrated and the required number thereof, in a given unit, a definite con-

trol and check is provided for substantially dispensing with excess moisture in the air admitted to and passed through the generator.

In the accompanying drawing, I have shown one arrangement of baffles to accomplish the desired result. It will be apparent, however, that this arrangement may be amplified or varied to suit different conditions, and particularly in increasing the number of baffles employed. It is preferred, however, that in the use of several baffles, that arrangements be had which will collect the condensation throughout the complete cross-sectional area of the air duct, so as to prevent any possible transmission of moisture directly down through the duct. It will be understood that the baffles, as seen in sections, in Fig. 2 of the drawing, extend completely across or join front and back walls of the air duct 14, as seen in Fig. 2. This has been indicated in dotted lines in Fig. 1 of the drawing.

In the present showing, the baffles are disposed cross-wise with respect to the circulating coils 16. It will be apparent, however, that the baffle may be disposed at right angles to the position shown, in which event, they would extend length-wise with respect to the coils.

It will be understood that baffles are arranged in the air duct in a manner to cause the air to be deflected in its circulation through the air duct, thus giving ample opportunity to displace the moisture. In this connection it will be apparent that the curved ends on the baffles materially aid in collecting and directing condensation to the drain discharges of said baffles. In addition to collecting condensation, it will also be understood that the baffles serve as means of eliminating water that might escape, by virtue of a leak, from the tubes. In other words, the baffles serve to eliminate transmission of moisture to the generator, which would materially affect the windings thereof.

Having fully described my invention, what I claim as new, and desire to secure by Letters Patent is:

1. A cooling system for apparatus of the class described, comprising an air duct having a horizontal top part terminating in depending ends opening directly into widely spaced depending sides, cooling means extending transversely through the upper portion of one side, means comprising a series of baffles vertically spaced in staggered relationship in said side of the air duct below said cooling means for collecting condensation, said baffles being arranged on opposed side walls of the duct and intermediate said opposed side walls, means for disposing condensation from each of said baffles outwardly of the air duct, the staggered arrangement of said baffles defining irregular circulating passages through said side of the duct, and means in said duct for providing forced circulation of air therethrough.

2. A cooling system for apparatus of the class described, comprising an air duct having a horizontal top part terminating in depending ends opening directly into widely spaced depending sides, cooling means extending transversely through the upper portion of one side, means comprising a series of baffles vertically spaced in staggered relationship in said side of the air duct below said cooling means for collecting condensation, said baffles being arranged on opposed side walls of the duct and intermediate said opposed side walls, means for disposing condensation from each of said baffles outwardly of the

air duct, the staggered arrangement of said baffles defining irregular circulating passages through said side of the duct, means in said duct for providing forced circulation of air therethrough, and all of the baffles terminating in curved free ends.

3. In cooling systems of the character described, comprising an air duct having vertical sides widely spaced and directly joined by a horizontal top portion having depending ends opening into said sides, means providing a forced circulation of air through said duct, means in the upper portion of one vertical side of the air duct for cooling air circulated therethrough, a plurality of baffles in said side of the air duct directly beneath said cooling means, said baffles being spaced vertically in the air duct and arranged to control circulation of air through said side of the duct, means for draining condensation collected by said baffles, one baffle being disposed centrally of the air duct between opposed walls thereof and having upwardly curved trough ends in spaced relation to other opposed walls of said duct to form air circulating passages between said curved ends and last named walls, and other baffles extending inwardly from said second named opposed walls and overlying ends of said first named baffle.

4. In cooling systems of the character described, comprising an air duct having vertical sides widely spaced and directly joined by a horizontal top portion having depending ends opening into said sides, means providing a forced circulation of air through said duct, means in the upper portion of one vertical side of the air duct for cooling air circulated therethrough, a plurality of baffles in said side of the air duct directly beneath said cooling means, said baffles being spaced vertically in the air duct and arranged to control circulation of air through said side of the duct, means for draining condensation collected by said baffles, one baffle being disposed centrally of the air duct between opposed walls thereof and having upwardly curved trough ends in spaced relation to other opposed walls of said duct to form air circulating passages between said curved ends and last named walls, other baffles extending from the last named walls upwardly in the direction of the central portion of the air duct, the upper ends of said last named baffles terminating in outwardly curved portions, and said curved portions being spaced apart to form centrally of the air duct an air circulating passage.

5. In cooling systems of the character described, comprising an air duct having vertical sides widely spaced and joined by a horizontal top portion, means providing a forced circulation of air through said duct, means in the upper portion of one vertical side of the air duct for cooling air circulated therethrough, a plurality of baffles in said air duct directly beneath said cooling means, said baffles being spaced vertically in the air duct and arranged to control circulation of air through said duct, means for draining condensation collected by said baffles, one baffle being disposed centrally of the air duct between opposed walls thereof and having upwardly curved trough ends in spaced relation to other opposed walls of said duct to form air circulating passages between said curved ends and last named opposed walls, other baffles extending from the last named upwardly in the direction of the central portion of the air duct, the upper ends of said last named baffles terminating in outwardly curved portions, said curved portions being spaced

apart to form centrally of the air duct an air circulating passage, another baffle disposed in the air duct beneath the first named baffle and said second named baffles, said last named baffle being in the form of a trough shaped member, and upper ends of the trough shaped member being curved inwardly and spaced from the second named opposed walls of said air duct.
